Specification for Design.

Patented Oct. 18, 1921.

Application filed March 5, 1921. Serial No. 450,105. Term of patent 7 years.

To all whom it may concern:

Be it known that I, JOHN WILLIAM SCHULZE, a citizen of the United States, and residing at Providence, in the county of Providence and State of Rhode Island, have invented a certain new, original, and ornamental Design for a Back for Lighting-Fixtures, of which the following is a specification, reference being had to the accompanying drawing, forming part thereof.

Figure 1 is a front view of a back for lighting fixtures, showing my new design.

Fig. 2 is a side elevation of the same.

I claim:

The ornamental design for a back for lighting fixtures, as shown.

JOHN WILLIAM SCHULZE.
